2,163,928

WALL FURNACE

John S. Andrews, Los Angeles, Calif.

Application June 18, 1937, Serial No. 148,932

4 Claims. (Cl. 126—90)

My invention relates to wall furnaces, more particularly a small furnace to be placed in the wall between two rooms for heating either or both rooms, and the objects of my invention are:

First, to provide a furnace of this class which may be placed in an eight inch partition for heating the adjoining rooms on opposite sides of said partition or either of said rooms;

Second, to provide a furnace of this class in which the side of the partition may be plastered over and all of the exposed area is the inlet and outlet grills for taking in the cold air and providing an exit for the outlet of the heated air;

Third, to provide a furnace of this class with means for deflecting the heated air to either of the rooms on the opposite sides of the partition;

Fourth, to provide a furnace of this class which provides means for taking air from the outside and passing it into the room with the heated air for supplying fresh air to the rooms;

Fifth, to provide a furnace of this class which may be placed between two studs of the partition and is insulated therefrom;

Sixth, to provide a novel heater casing for furnaces of this class;

Seventh, to provide a novel circulating air means for heaters of this class;

Eighth, to provide novel venting means for furnaces of this class which diverts back drafts from the flue;

Ninth, to provide novel heat distributing means for wall furnaces;

Tenth, to provide a novelly constructed furnace of this class which is very simple and economical of construction, easy to install, efficient in its action, and which will not readily deteriorate or get out of order.

With these and other objects in view as will appear hereinafter, my invention consists of certain novel features of construction, combination, and arrangement of parts and portions as will be hereinafter described in detail and particularly set forth in the appended claims, reference being had to the accompanying drawings and to the characters of reference thereon which form a part of this application in which:

Figure 1 is a vertical sectional view through the middle of my furnace showing some of the parts and portions in elevation to facilitate the illustration; Fig. 2 is a sectional view from the line 2—2 of Fig. 1; Fig. 3 is a transverse sectional view from the line 3—3 of Fig. 1 showing some of the parts in elevation to facilitate the illustration; Fig. 4 is an enlarged sectional view of a fragmentary portion taken from the line 4—4 of Fig. 1;

Fig. 5 a sectional view from the line 5—5 of Fig. 4; Fig. 6 is a side elevational view of one side of the furnace and showing some of the parts in section; Fig. 7 is a transverse sectional view from the line 7—7 of Fig. 1; Fig. 8 is a similar view from the line 8—8 of Fig. 1; Fig. 9 is a similar view from the line 9—9 of Fig. 1; Fig. 10 is a similar view from the line 10—10 of Fig. 1; Fig. 11 is a similar view from the line 11—11 of Fig. 1; and Fig. 12 is a similar view from the line 12—12 of Fig. 1.

Similar characters of reference refer to similar parts and portions throughout the several views of the drawings.

The heater casing 1, heat distributing casing 2, vent 3, burner 4, air conducting casing 5, outer casing 6, cold air inlet grills 7 and 8, hot air outlet grills 9 and 10, asbestos lining 11, shiftable deflector 12, stationary deflectors 12b and 12c, partitions 13 and 14, tile vent 15, and shield 16 constitute the principal parts of my wall furnace.

This wall furnace is positioned between two studding S which are substantially two-by-eights and with a header H at the top, and supported above the floor by means of cross beams B which form the support at the bottom and are positioned on the floor F. Mounted in this space between the studding, header, and beams is a metallic casing 6 which is closed on all sides but is provided on each side at the bottom with open spaces over which are mounted the cold air inlet grills 7 and 8 which are secured to this casing over said openings; also at the upper side are provided openings at opposite sides over which are secured the heated air outlet grills 9 and 10. Positioned between the outer side of this casing 6 and the studding and heater is an asbestos lining 11, which protects the studding and other woodwork from the metal casing. Also on the opposite sides between the heated air grills 9 and 10 and the cold air grills 7 and 8 is provided asbestos lining 11. Positioned on the outside of this asbestos lining 11 is plaster supporting wire W over which is provided a plaster covering P so that the sides of the heater are covered at the exterior with plaster so that nothing shows except the grills in the upper and lower sides of the furnace as shown best in Fig. 6 of the drawings.

Mounted centrally in the casing 6 and directly over a burner 4 is the heater casing 1 which is hollow and rectangular and extends substantially one-half the height of the furnace. This casing 1 is open at its upper end 1a except for the short ends 1b. Below the end 1a is a baffle member 1c which is shaped as shown best in Fig. 10 of the drawings leaving two opposed open spaces 1d and 1e.

le for the heated air to pass through and be circulated upwardly. Below this baffle member 1c is another baffle member 1f shaped as shown best in Fig. 11 of the drawings with open spaces on opposite sides from the baffle 1c as disclosed by 1g and 1h, and below the baffle member 1f is another baffle member 1i and this baffle member is shaped as shown best in Fig. 12 with two openings 1j and 1k.

10 Superposed above the heater casing 1 and extending downwardly around the upper side thereof is heat distributing casing 2 which is box-shaped and open at its lower side so that the edge extends down over the casing 1 a short distance. It is provided at its upper side with a central orifice 2a from which extends upwardly a vent 3 which is cylindrical in form and provided over its upper end is a conical cover 3a and leaving an open space 3b above said vent immediately below this cover 3a. This heat distributing casing 2 is provided with a transversely positioned baffle member 2f shaped as shown best in Fig. 7 of the drawings and leaving two openings 2g and 2h and below this baffle is another 25 baffle 2i which is provided with two openings 2j and 2k. Thus it will be noted that the heat from the burner 4 is baffled in a zigzag course to the orifice 1b; then it is again baffled in a zigzag course to the vent 3, and then passes upwardly 30 through the flue 15 which is composed of tile or similar subject matter which is spaced from the header H as shown by space 15a and provided by a cover plate 15b. Positioned in the lower end of the vent 15 and surrounding the upper end of 35 the vent 3 is a conducting member 17 which conducts the exhaust from the burner upwardly into the flue 15. Positioned on opposite sides of the vent 3 and secured at its ends and to the vent 3 is a deflector 12b which is shaped as shown best in 40 Figs. 2 and 4 of the drawings consisting of an upper straight portion 12a, two angular portions 12b and 12c which connect near the middle of the member 12a in spaced relation therefrom and pivotally mounted at the lower extremity is a 45 downwardly extending pendant portion 12. This member 12 is adapted to be shifted on its pivotal axis to position shown by dash lines in Fig. 2 of the drawings or may be shifted in the opposite direction, and is for the purpose of directing 50 the heat from around the heater casing 1 and heat distributing casing 2 to a room at either side of the partition in which the furnace is mounted. However, when the pendant 12 extends straight down as shown by solid lines, the 55 heat then is distributed in both directions to the rooms on the opposite sides, it being noted that the pendant member 12 is adapted to come in substantial alignment with the lower edge of the grilles 9 or 10 which confine the air passing upwardly through the inlet grilles 7 and 8 60 upwardly along the heater casing and heat distributing casing and upwardly so that it passes out through the outlet grilles 9 and 10 regulated by the shiftable deflector 12. Interposed between the partition 13 and the outer walls of the 65 heater casing 1 and the heat distributing casing 2 are partitions 14 which tend to further distribute the air passing upwardly and adds to the efficiency of the heating surface by conduction 70 from the heater casing and heat distributing casing.

Positioned between the ends of the casing 5 and the heater casing 1 are upwardly extending offset supporting members 18 and the lower side 75 of which forms the floor 18a of the furnace

mounted on the upper beam B. It will be here noted that the floor and beam B are cut away to provide passages C for cold air coming up from under the floor which passes upwardly between the ends 5 and casing 6 and passes out through the upper openings in the grilles 9 and 10 into the rooms to supply fresh air in the rooms which is heated on its way upwardly. 5

The shield 16 extends upwardly between the grilles 7 and 8 to the lower side of the heater 10 casing 1 and serves to prevent drafts through from one of the grilles 7 to the grille 8.

Though I have shown and described a particular construction, combination, and arrangement of parts and portions, I do not wish to be limited 15 to this particular construction, combination, and arrangement, but desire to include in the scope of my invention the construction, combination, and arrangement substantially as set forth in the appended claims. 15

Having thus described my invention, what I 20 claim as new and desire to secure by Letters Patent is:

1. In a wall furnace, a relatively wide and extremely thin heater casing provided with zigzag 25 current directing baffles, a burner positioned at the lower end thereof arranged to direct heat upwardly through said baffles, said casing open at its upper end, a heat distributing casing supported around the upper end of said heater casing and provided with similarly arranged baffles, and an orifice at its upper end, a deflector positioned above said heat distributing casing provided with a downwardly depending shiftable member and adapted to be shifted on a pivotal 30 axis for directing the hot air from said heat distributor, an outer casing spaced from said heater casing and heat distributing casing provided with inlet grilles near its lower end and outlet grilles near its upper end for circulating air past the 35 wall of said heater casing and said heat distributing casing and through the rooms on opposite sides of the heater, and metallic partitions and deflectors interposed between said heat distributing casing and outer casing. 40

2. In a wall furnace, a relatively wide and extremely thin heater casing provided with zigzag current directing baffles, a burner positioned at the lower end thereof arranged to direct heat upwardly through said baffles, said casing open at its upper end, a heat distributing casing supported around the upper end of said heater casing and provided with similarly arranged baffles, and an orifice at its upper end, a deflector positioned above said heat distributing casing provided with a downwardly depending shiftable member adapted to be shifted on a pivotal axis for directing the hot air from said heat distributor, an outer casing spaced from said heater casing and heat distributing casing provided with inlet grilles near its lower end and outlet grilles near its upper end for circulating air past the 50 wall of said heater casing and said heat distributing casing and through the rooms on opposite sides of the heater, metallic partitions and deflectors interposed between said heat distributing casing and outer casing, and a space between said outer casing and said heater casing being open through the floor for admitting air from the outside for circulation past the end walls of the 55 heater and out through the upper openings in the upper grilles. 60

3. In a wall furnace, a relatively wide extremely thin heater casing adapted to be positioned between the studding between the conventional 75

flat walls of a building, a heat distributing casing positioned centrally therein provided with an outlet orifice at its upper end, a deflector positioned above said heat distributing casing provided with a downwardly depending shiftable member adapted to be shifted on a pivotal axis for directing the hot air from said heat distributing casing, an outer casing spaced from said heater casing and said heat distributing casing provided with inlet grills near its lower end and outlet grills near its upper end for circulation of air past the wall of said heater casing and said heat distributing casing and through the rooms on opposite sides of the heater, metallic partitions and deflectors interposed between said heat distributing casing and outer casing leaving a space between said outer casing and said heater casing which is open through the floor for admitting air from the outside for circulation past the end walls of the heater and out through the upper openings in the upper grills for both ventilating the room and serving as insulation between the building wall and the heater at the opposite ends of said heater.

4. In a wall furnace, a relatively wide extremely thin heater casing adapted to be positioned between the studding between the conventional flat walls of a building, a heat distributing casing positioned centrally therein provided with an outlet orifice at its upper end, a deflector positioned above said heat distributing casing provided with a downwardly depending shiftable member adapted to be shifted on a pivotal axis for directing the hot air from said heat distributing casing, an outer casing spaced from said heater casing and said heat distributing casing provided with inlet grills near its lower end and outlet grills near its upper end for circulation of air past the wall of said heater casing and said heat distributing casing and through the rooms on opposite sides of the heater, and metallic partitions and deflectors interposed between said heat distributing casing and outer casing at the ends leaving a space between the outer casing and said heater casing at the ends open through the floor for admitting air from the outside for circulation upwardly.

JOHN S. ANDREWS.
